[57] **CLAIM**

The ornamental design for a scarf hanger, as shown and described.

DESCRIPTION

FIG. 1 is a front perspective view of a scarf hanger showing my new design, the side opposite that shown being identical except for the hook;

FIG. 2 is a front elevational view thereof, the rear elevational view being a mirror image;

FIG. 3 is a top plan view thereof; and,

FIG. 4 is a bottom plan view thereof.
